Patented July 6, 1915.

UNITED STATES PATENT OFFICE.

IRWIN F. KEPLER, OF AKRON, OHIO, ASSIGNOR, BY MESNE ASSIGNMENTS, TO THE
B. F. GOODRICH COMPANY, A CORPORATION OF NEW YORK.

WATER BAG OR BOTTLE.

1,145,687.

Specification of Letters Patent.

Patented July 6, 1915.

Original application filed January 17, 1912, Serial No. 671,673. Divided and this application filed April 4, 1912. Serial No. 688,436.

To all whom it may concern:

Be it known that I, IRWIN F. KEPLER, a citizen of the United States, residing at Akron, in the county of Summit and State 5 of Ohio, have invented certain new and useful Improvements in Water Bags or Bottles, of which the following is a specification.

My present invention pertains to an improved water-bag or bottle, the same being 10 illustrated in the annexed drawings, wherein:

Figure 1 is a perspective view of the bag, a part of the edge or marginal portion being broken away to illustrate the construction of such portion; Fig. 2 a longitudinal sectional view of the bag, showing the molds in which it is finally formed and the thimble or valve-socket which is vulcanized in the throat of the bag; Fig. 3 an end elevation, partly in section, of the bag and the molds, 15 the same being on a somewhat enlarged scale; and Fig. 4 a perspective view of the combined thimble or socket-carrier and the funnel mold.

The object of the present invention is to 20 produce a bag or bottle without the use of seam-covering strips, separate throat pieces or the like which, as well known, are the weak points in such bag structures, frequently being the cause of the development 25 of leaks. Furthermore, the bag which forms the basis of the present invention has a threaded thimble or socket-piece, vulcanized in position during the process of manufacture of the bag or bottle, thereby 30 insuring a tight joint between such member and the throat of the bottle.

The method by which the bag covered by 35 the present application is produced forms the subject-matter of my co-pending application filed on or about January 17, 1912, 40 Serial No. 671,673, the present case being a division thereof.

In order that the invention may be clearly 45 understood, a general statement of the process by which the bag or bottle is produced will be given. The bag is produced in half-sections, each section being formed in a mold and partially cured. The marginal portion 50 of each section is forced outwardly over the edges of the mold beyond the ultimate edge of such section, the fin or protruding portion thus formed being severed or cut off so as to produce a homogeneous surface or edge. The two halves thus formed are then placed face to face and the bag is finally 55 vulcanized. Prior to the complete vulcanization, however, the socket or thimble is positioned in the mouth of the bag and vulcanized in place at the same time that the marginal portions are secured to each other 60 by such vulcanization. During the process of producing the half sections, the marginal portions are thickened and provided with a projection which, when the parts are finally 65 vulcanized, forms a bead around the outer edge of the bag and, owing to the pressure exerted by the molds, a fin is likewise produced upon the inner portion of the bag along the line of contact of the marginal 70 portions of the two sections where they are brought together prior to the final vulcanization.

Referring to the drawings in which the final molds are alone shown, 1 denotes one member of the mold and 2 the opposite member. The funnel-mold and socket-carrier 3 are shown in Figs. 2 and 4, the same being 75 designed to coact with the mold sections 1 and 2 to form the funnel 4, and the tab or projection 5 thereon, and likewise to carry 80 the socket or threaded nipple 6, which is vulcanized in place in the throat of the bag while the two sections are being finally 85 united.

In Figs. 2 and 3 the two half-sections of 90 the bag, which are ultimately secured together, are denoted by 7, and where they are joined together at their edges there is produced a thickened edge or marginal portion 8, having a bead 9 extending along the outer 95 edge thereof entirely around the bag up to the throat 10 thereof. Said bead merges at the lower end of the bag into a tab 11, having an eyelet 12 therein. A fin 13 is preferably formed upon the inner face of the bag 100 or bottle opposite the bead 9, said fin, bead and thickened marginal portion rendering the bag stronger at those points where ordinarily such bags are the weakest. In other words, there is produced a bag which is 105 virtually an integral structure throughout, without seam or joint, and having the valve-socket firmly vulcanized in place in the throat 10. The reinforced edge insures strength and stability in the structure.

Having thus described my invention, what I claim is:

1. As a new article of manufacture, a

seamless rubber bag having an integrally-formed thickened marginal portion with a bead extending around the outer edge of the same, and a fin or bead extending around the inner portion of the bag adjacent to the thickened marginal portion and formed as an integral portion thereof.

2. As a new article of manufacture, a seamless rubber bag having a thickened edge or marginal portion, with integrally-formed

strengthening projections extending around the same upon the inner and outer faces thereof.

In testimony whereof I have signed my name to this specification in the presence of 15 two subscribing witnesses.

IRWIN F. KEPLER.

Witnesses:

WALTER F. MEANS,

ILLA N. KIRN.
